Primary Examiner — Karen S Acker*(74) Attorney, Agent, or Firm* — Hauptman Ham, LLP(57) **CLAIM**

The ornamental design for a leather sheet, as shown and described.

DESCRIPTION

FIG. 1 is a surface view of a leather sheet according to our new design;

FIG. 2 is a reference view of FIG. 1, with dot dash broken lines shown therein to identify the area 3 which the detail view, FIG. 3, is taken; and,

FIG. 3 is an enlarged detail view of the area 3 circumscribed by dot dash broken lines within FIG. 2.

The leather sheet is intended to be used for an automobile interior material.

The broken lines surrounding FIGS. 1 and 2 represent the boundaries of the claim and form no part thereof. The dot dash dot broken lines within FIG. 2 and surrounding FIG. 3 represent the boundaries of the detail area and form no part no part of the claimed design.

The rear of the leather sheet is not included in the claim.
